UNITED STATES PATENT OFFICE.

ROBERT E. JACKSON, OF VICTORIA, AND FRANK E. BELL, OF NORFOLK, VIRGINIA.

SPARK-ARRESTER.

1,123,301.

Specification of Letters Patent.

Patented Jan. 5, 1915.

Application filed January 19, 1914. Serial No. 813,023.

To all whom it may concern:

Be it known that we, ROBERT E. JACKSON and FRANK E. BELL, citizens of the United States, residing at Victoria, in the county of 5 Lunenburg, and Norfolk, in the county of Norfolk, respectively, both in the State of Virginia, have invented new and useful Improvements in Spark-Arresters, of which the following is a specification.

10 Our present invention pertains to spark arresters, and consists in the peculiar and advantageous spark arrester, herein described and claimed, designed more particularly as an improvement upon the spark 15 arrester constituting the subject of our temporary application, filed April 17, 1913, Serial Number 761,796.

In the drawings, accompanying and forming part of this specification: Figure 1 is a 20 view showing the smoke box and fire box of a locomotive boiler, with our improvement properly applied. Fig. 2 is a transverse section taken in the plane indicated by the line 2—2 of Fig. 1.

25 Similar numerals of reference designate corresponding parts in both views of the drawings.

The locomotive boiler 1 is provided with flues 1^x, a smoke box 2 from which rises an 30 uptake 3, and a fire-box 4. These parts may be and preferably are of the ordinary well known construction. We also employ, by preference, the ordinary exhaust pipe 5, aligned with the uptake 3, and arranged conventionally or otherwise in communication 35 with the exhaust cavities in the saddles of the piston cylinders of the locomotive.

Arranged in the lower portion of the pipe 5 is the bell-shaped or flaring mouth 6 of an 40 auxiliary conduit 7 for exhaust steam, which conduit extends through the wall of and forwardly from the pipe 5, as shown.

The smoke box 2 is divided into compartments, one of which is in full and free 45 communication with the flues 1^x, and the other in full and free communication with the uptake 3. The said division is effected through the medium of a diaphragm that comprises a rear imperforate portion 8 50 through which the pipe 5 extends, and a forward foraminous portion 9; said foraminous portion being inclined downwardly and rearwardly as illustrated. The lower and forward portion of the imperforate

plate 8 is preferably extended below the 55 lower and rear end of the foraminous portion 9 as shown.

Extending rearwardly and downwardly from the forward wall of the smoke box 2 is a chute 10—i. e., a wall adapted to receive 60 cinders that drop from the screen 9, and shed said cinders in the lower forward portion of the smoke box. Below the lower and rear edge of the chute or wall 10 is the flared mouth 11 of a conduit 12, which flared 65 mouth may be of the proportional width shown in Fig. 2, or may be extended throughout the width of the lower portion of the smoke box without affecting our invention. 70

Above the chute or wall 10, the conduit 12 is connected with two conduits 13, and these extend rearwardly at points outside the boiler, and are respectively equipped with a suitable non-return valve 14, arranged to 75 open toward the fire box 4, and a valve-controlled air-induction conduit 15. The conduit 12 and the conduits 13 are not reduced or obstructed at any point in their length, and hence there is no liability of 80 said conduits being cut or worn by cinders drawn or forced therethrough. The valves 14 in the pipes 13 do not interfere in any measure with the passage of products of combustion toward the fire-box, but they 85 preclude passage of gases, etc., in the opposite direction under all conditions.

As will be readily observed, the valves of the air-induction conduits 15 may be opened when it is desired to supply atmospheric air 90 to the conduits 13 with a view to supporting combustion in the fire-box.

The conduits 13 may be led into the fire-box in any approved manner, and at any desired points without involving departure 95 from the scope of our invention. We prefer, however, to connect each conduit 13 with the fire-box in the manner shown in Fig. 1—that is by carrying the conduit through a sleeve 16 in the water leg of the 100 boiler, and connecting it to a refractory conduit section 17 which, in turn, communicates with a flared mouth 18 in the front wall 19 of the fire-box 4; said mouth 18 being adapted to spread the hot gases and other products of combustion above the fire in the fire-box. 105

An auxiliary valved blower 20 leads from

a suitable point in the boiler to the flared mouth 11 of the conduit 12, where it has a discharge as shown. By opening the valve 21 in the conduit 20 the engineer in his cab 5 is enabled to send a jet of steam into the mouth 11, and in that way create suction in said mouth and clear the smoke box of collected smoke when the engine is drifting and there is no discharge of exhaust steam 10 through the pipe 5 and the conduit 7.

In the practical operation of our improvement, and when the valve 21 in the conduit 20 is closed, the exhaust steam passing through the pipe 5 will create a partial 15 vacuum in the shoulder in front of the diaphragm 8-9, and consequently the gaseous products of combustion will be forcibly drawn through the diaphragm portion 9 and discharged through the uptake 3. The 20 passage of sparks and cinders through said diaphragm portion 9 will, however, be effectually prevented. This latter is due in large measure to the partial vacuum created in the conduit 12 by the discharge therein of 25 exhaust steam from the conduit 7, since thereby a portion of the smoke and heated air and gases, together with sparks and cinders, will be forced through the conduits 12 and 13 and back to the fire-box.

30 It will be noted here that in entering the fire-box through the conduit-section 17, the returned products of combustion are heated, and hence adapted to promote combustion in the fire-box.

35 Having described our invention, what we

claim and desire to secure by Letters-Patent, is:

1. The combination in a locomotive, of a boiler having a water leg, a fire-box and a smoke-box, said fire-box having a rearwardly-directed discharge conduit in the upper portion of its front wall, a conduit section of refractory material extending between the water leg and the front wall of the fire-box and communicating with said discharge conduit, and a conduit for products of combustion extending from the smoke-box to said conduit section. 45

2. The combination in a locomotive, of a fire-box, a smoke box, a foraminous diaphragm arranged in the upper forward portion of the smoke box, a rearwardly and downwardly inclined chute disposed in the smoke box below said diaphragm and extending from the front wall of the smoke 55 box, a conduit for products of combustion extending between the fire-box and the smoke box and having a rearwardly-directed flared mouth disposed in the latter and under the said chute, and means for discharging steam forwardly into said mouth. 60

In testimony whereof we have hereunto set our hands in presence of two subscribing witnesses.

ROBERT E. JACKSON.
FRANK E. BELL.
